HOBBYHORSE OR SIMILAR ARTICLE

Edward J. Koller, Collierville, Tenn.

Application February 28, 1952, Serial No. 18,704

Term of patent 14 years

(Cl. D34—15)

To all whom it may concern:

Be it known that I, Edward J. Koller, a citizen of the United States and a resident of the city of Collierville, in the county of Shelby and State of Tennessee, have invented a new, original, and ornamental Design for a Hobbyhorse or Similar Article, of which the following is a specification, reference being had to the accompanying drawing, forming a part thereof.

In the drawing:

Figure 1 is a side elevational view of the hobbyhorse or similar article, showing my new design;

Figure 2 is a plan view of the body of the hobbyhorse;

Figure 3 is a rear elevational view thereof; and Figure 4 is a front elevational view thereof.

The essential features of my design are shown in full lines.

I claim:

The ornamental design for a hobbyhorse or similar article, as shown and described.

EDWARD J. KOLLER.
